UNITED STATES PATENT OFFICE.

EMMIT G. LATTA, OF FRIENDSHIP, NEW YORK, ASSIGNOR OF ONE-HALF TO
ADRIAN C. LATTA, OF SAME PLACE.

BICYCLE.

SPECIFICATION forming part of Letters Patent No. 280,633, dated July 3, 1883.

Application filed January 30, 1883. (No model.)

To all whom it may concern:

Be it known that I, EMMIT G. LATTA, of Friendship, in the county of Allegany and State of New York, have invented a new and useful Improvement in Bicycles, of which the following is a specification.

This invention relates to an improvement in bicycles, and has for its object to produce a machine which is simple, strong, and durable in construction, which can be readily repaired, and which can be easily operated.

My invention consists, to that end, of the improved construction of the steering-head, whereby the latter is rendered self-adjusting; also, of the construction of the axle, whereby the latter can be readily repaired; also, of the construction of the bearings of the driving-wheel, whereby the frictional point is located on the under side of the axle; also, of the construction of the crank, whereby it is rendered stronger and easily adjustable; also, of the construction of the spokes, whereby the latter can be attached after the tire has been applied to the rim, and which enables the spokes to be readily removed and replaced by new ones without disturbing the rim of the wheel; also, of the construction of the rim, whereby the rim is rendered stronger than heretofore; and, also, of the construction of the tire, and of the means whereby it is secured to the rim, as will be hereinafter fully described, and pointed out in the claims.

In the accompanying drawings, consisting of four sheets, Figure 1 is a cross-section of the steering-head and the upper portion of the driving-wheel. Fig. 2 is a cross-section of the central portion of the driving-wheel. Fig. 3 is a cross-section in line $x x$, Fig. 2. Fig. 4 is a side elevation of the inner portion of the crank. Fig. 5 is a horizontal section in line $y y$, Fig. 2. Fig. 6 is a cross-section in line $z z$, Fig. 5. Fig. 7 is a sectional view, on an enlarged scale, of a portion of the hub. Fig. 8 is a fragmentary sectional elevation of a portion of the rim of the wheel. Fig. 9 is a partly-sectional face view of the rim. Fig. 10 is a cross-section of the rim on an enlarged scale. Fig. 11 is a cross-section of the rubber tire before it is secured to the rim. Fig. 12 is a vertical section of the steering-head at right angles to Fig. 1. Figs. 13 and 14 are cross-sections

in lines $x x$ and $y y$, Fig. 12, respectively. Fig. 15 shows a modified construction of the bearings of the wheel. Fig. 16 is a sectional view, illustrating the manner of applying the spokes 55 to the wheel.

Like letters of reference refer to like parts in the several figures.

A represents the backbone or reach of the machine, provided at its front end with the usual upright center-pin, a .

B represents the forks which straddle the driving-wheel, and which are provided at their upper ends with a socket or head, B', which 60 incloses the center-pin a .

C represents a socket or cylindrical cap, which is secured in the upper portion of the socket B by a screw-thread, c , and C' is a follower, which is seated with its upper cylindrical end in a correspondingly-shaped recess 65 70 in the cap C, and which fits over the upper end of the center-pin, a , and rests upon the upper end thereof.

c' is a spiral spring which surrounds the follower C', and which rests with its upper end 75 against a shoulder, c' , formed in the cap C, and with its lower end against a collar or flange, c' , formed on the lower end of the follower C'. The spring c' forces the follower C' downwardly and against the upper end of the center-pin a , and holds the follower in close contact with the center-pin, and the lower end of the latter in close contact with its seat in the head B'. The arrangement of the spring c' around the center-pin a renders the device 80 85 more compact and permits the use of a longer center-pin than heretofore without increasing the height of the steering-head.

C' represents a perforated lug formed on the socket B' for the reception of the handle-bar. 90

D represents the hollow cylindrical body or central portion of the axle of the driving-wheel, and D'D' represent the end portions of the axle, which are secured to the outer ends of the body D by screw-threads d .

E E represent the hubs of the driving-wheel, which are secured to the ends of the body D of the axle by screw-threads e , and by wedge-keys e' , which pass through the hubs, the body D, and the end portions, D', of 95 100 the axle, as clearly shown in Figs. 5 and 6. This construction of the axle permits each

end of the axle to be readily removed and replaced by a new one when broken. Each of the bearings whereby the axle of the driving-wheel is connected with the forks B is constructed in three parts, the central part, F, being secured to the lower end of the fork by means of lugs f f' , formed, respectively, on the bearing and on the fork, and a horizontal bolt, f^2 , passing through said lugs. The inner portion, G, of the bearing is secured to the hub D by means of a screw-thread, g , so that this portion of the bearing can be adjusted toward or from the central portion, F, by screwing it into or out of the hub, as may be required. The outer portion, H, of the bearing is formed in one piece with the outer portion, D', of the axle. The central portion, F, of the bearing is provided with a bore, f^3 , which is made somewhat larger than the axle D', which passes through the bearing, so that the bearing F does not come in contact with the axle at any point.

h represents two series of balls which are interposed between the adjacent surfaces of the central portion, F, and the inner and outer portions, G and H, of the bearing, the adjacent faces of these parts being grooved to receive and hold the balls, as clearly shown in Figs. 2 and 5. By this construction of the bearings the weight applied to the forks is supported by the balls on the under side of the axle, thereby locating the point of frictional contact between the parts under the axle, instead of over the same, as is ordinarily the case. This construction affords a long leverage to the crank at the first and most essential part of the stroke, and also shortens the leverage from the ground to the bearings, thereby enabling a large wheel to be driven with the same pressure required for a small wheel turning in ordinary bearings. This arrangement also causes the balls to remain at the frictional point by gravity, instead of tending to work away from it, which is especially important after the bearings have become worn, so that there is a space between the balls. The same arrangement may be applied to bearings having a single series of balls with an axle and crank as ordinarily constructed, as represented in Fig. 15, and also to double or single parallel bearings, in which case the balls are left out and the parts G and H fitted directly to the central portion, F. In all of these constructions a wheel having a fixed axle has its point of frictional contact with the bearing arranged in the same manner as a loose wheel revolving on a fixed axle.

I represents the cranks, secured to the outer ends of the end portions, D', of the axle. The latter are provided with grooves i , in which the inner ends of the cranks are adjustably secured by set-screws i' , engaging in threaded holes in the end portions, D', of the axle. These set-screws are provided with conical heads, which engage in slots i^2 , having beveled sides, and formed in the inner ends of the cranks. Upon loosening the set-screws i' , the

cranks can be adjusted toward or from the axis of the axle, and by tightening the set-screws they are secured in the desired position. The faces of the end portions, D', of the axle are each provided with projecting ribs i^3 , which fit in the slots i^2 , between the jaws of the crank, and relieve the set-screws from the strain of the crank. This construction is very desirable, as it permits a close build and a large diameter of the wheel, with less distance between the pedals, and saves the cranks in case of a fall, when the set-screw will be broken, which is easily replaced, instead of the cranks or the axle being bent or broken, and as the pedal-pin and crank are made in one piece there is no danger of the pedals getting loose, and the outer ends of the crank can be made lighter than where the pedals are adjustably attached to the crank.

J represents a shield composed of a concave or dished plate, which is applied to the outer side of the inner end of the crank, for the purpose of preventing the crank from catching the clothing, and for protecting the bearings from dust. The shield J is provided with an opening, j , through which the crank passes, and with an opening, j' , near its center, through which the head of the set-screw is rendered accessible. The shield is provided on its inner side with a spring-catch, j^2 , which engages under the head of the set-screw and holds the shield in place on the crank.

k represents a ring or rim which surrounds the bearing, and which projects with its outer edge beyond the inner edge of the shield J, and with its inner edge beyond the outer edge of the hub E, as clearly shown in Fig. 2. The ring k is secured to the fork B, and the hub, ring, and shield inclose the bearing, and substantially protect the same from dust.

When it is desired to oil the bearings or tighten them, one side of the shield J is lifted, so as to disengage the catch j^2 from the set-screw, when the shield can be moved outwardly on the crank to the position represented in dotted lines in Fig. 2, whereby the bearing is rendered accessible.

L represents the spokes, which are secured with their inner ends to the hubs E, and with their outer ends to the rim M. The rim is composed of two strips of sheet metal, each having approximately a U-shaped cross-section, with one side longer than the other, and both strips being fitted upon each other in such a manner that the inner and outer plate of one strip overlaps and rests against the corresponding plate of the other strip, both together forming a hollow rim having a concave face, m , and two thicknesses of metal at the central portion of the concave face and at the inner side of the rim, where the outer ends of the spokes pass through these parts, as clearly represented in Fig. 10. The strips of which the rim M is composed are beaded on their inner sides, as shown at m' , in order to hide the joint or laps of the two strips composing the rim. The inner ends of the spokes L are provided with screw-

threads l , which engage in sockets formed in the peripheral portions of the hubs E. These sockets are arranged in a raised marginal flange, E', of the hub, and extend through this 5 raised flange, so that when the wheel is detached from the frame the inner ends of the spokes can be reached with a screw-driver or other suitable tool for turning the spokes in their sockets. The inner portions, l' , of the sockets are 10 screw-threaded, and their outer portions, l'' , are made large enough to permit the spokes to pass through the same. The inner ends of the spokes are notched or otherwise constructed so that the spokes can be turned by applying a 15 screw-driver or other suitable tool when it becomes necessary to remove the end of a broken spoke.

For applying new spokes a spoke-grip is used. The outer ends of the spokes L are provided 20 with screw-threads l'' , which engage in blocks N, seated in the hollow rim M. These blocks are made square or polygonal, and the rim is provided with correspondingly-shaped openings, in which the blocks are held against turning. The blocks are provided with screw-threaded openings, in which the outer ends of 25 the spokes engage. The screw-threads l'' at the outer ends of the spokes are made coarser or of greater pitch than the screw-threads at 30 the inner ends of the spokes. The spokes are applied to the wheel by screwing their inner ends through the sockets of the hubs until their outer ends pass beyond the inner end of the rim M, so that their outer ends can be placed 35 in line with the blocks N, as represented in Fig. 16. The spokes are then screwed outwardly through the sockets of the hubs and into the openings of the blocks N. As the screw-threads of the outer ends of the spokes 40 are of a greater pitch than those at the inner ends, this operation will draw the rim toward the hub, and thereby give the rim the necessary tension at the same time that the spoke is connected with the rim. This means of applying 45 the spokes to the wheel permits the insertion and removal of each spoke without disturbing any other part of the rim or requiring the removal of the tire, and does away with the necessity of heading the spokes after they 50 are put in place.

O represents the tire, which is secured in the concave outer face of the rim M. This tire is constructed of a strip of rubber or other suitable yielding material, having the side which 55 is designed to rest against the rim of the wheel made flat, or nearly so, as represented at o' , and a groove, o'' , arranged in its outer side. This tire is secured in the concave face of the rim by means of a metallic binder, p, which is 60 placed in the groove o'' , and by screws p' , which pass through the binder p and the inner portion of the tire and engage in the threaded opening in the inner portion of the rim, as clearly shown in Fig. 10. Upon tightening 65 the screw p' the tire O is forced into the concave face of the rim, whereby the outer ends of the side portion of the tire are caused to ap-

proach each other until they come in contact and close the opening o' , as represented in Fig. 10. The binder p may be made in one 70 piece extending all around the wheel; but I prefer to construct it of several short pieces which overlap each other at their ends. The screws p' pass through the overlapping ends of the pieces of which the binder is composed, 75 as represented in Figs. 8 and 10. The screws may be inserted from the outside, as shown, or they may be reversed and screwed through an opening in the rim into the binder, if preferred. The tire, secured as herein described, 80 does not slip or become loose, and as the rubber is compressed instead of being stretched, as it is in tires tightened in the ordinary manner, the tire does not spread when cut. This 85 construction is also well adapted for repairing a tire, if the tire is constructed as herein described and cemented in the groove of the rim. If a portion of such a tire should become loose, it can be quickly secured by inserting a short binder into the groove of the 90 loose portion, and securing it by screws, as hereinbefore shown and described.

I am aware that tires have been secured to the rim by means of a metallic core arranged within the tire and secured by screws to the 95 rim; but these cores cannot be removed or replaced at will, like the binder herein described.

I claim as my invention—

1. The combination, with the center-pin a, of the socket B', cap C, follower C', and spring 100 c', surrounding the center-pin, substantially as set forth.

2. The combination, with a wheel, of an axle secured to the wheel, a bearing secured to the fork or frame of the machine, through 105 which the axle passes without touching the bearing, and a bearing secured to the axle, upon which the bearing secured to the fork or frame rests, on the under side of the axle, substantially as set forth.

3. The combination, with the bearing F, secured to the fork or frame of the machine, of the axle D', secured to the wheel, and passing through the bearing F without touching the same, inner and outer bearings, G and H, secured to the wheel, and two series of balls, h, interposed between the bearings F, G, and H, whereby the bearing F rests upon the balls on the under side of the axle, substantially as set forth.

4. The combination, with a bearing, F, secured to the fork or frame of the machine, of the axle D', secured to the wheel, and passing through the bearing F, without touching the same, a bearing, H, secured to the axle, and a 115 bearing, G, secured adjustably to the hub, substantially as set forth.

5. The combination, with the central portion, D, of the axle, of the end portions, D', removably attached to the central portion, D, 120 substantially as set forth.

6. The combination, with the central portion, D, of the axle, of the hubs E and end portions, D', secured to the central portion, D, by

- serew-threads *d* and *e* and bolts or keys *e'*, substantially as set forth.
7. The combination, with the axle D', provided in its end or face with a groove, *i*, of a 5 crank, I, fitted in the groove *i*, and provided with a slot, *i'*, and a set-serew, *i'*, whereby the crank is secured to the axle D', substantially as set forth.
8. The combination, with the axle D', having its face or end constructed with a groove, *i*, and projection *i'*, of a crank, I, provided with a slot, *i'*, and a set-serew, *i'*, substantially as set forth.
9. The combination, with a shaft, D', crank 15 I, and set-serew *i'*, of the detachable shield J, having a spring-catch, *j'*, substantially as set forth.
10. The combination, with a hub, E, of the ring *k*, secured to the fork, and the shield J, 20 attached to the end of the shaft, whereby the bearing is inclosed and protected, substantially as set forth.
11. The combination, with the raised rim or flange E' of the hub, provided with screw-threaded sockets extending through the flange, 25 of serew-threaded spokes having their ends constructed to receive a serew-driver or wrench for removing the end of a broken spoke from the socket, substantially as set forth.
12. The combination, with a hub and rim of 30 a wheel, of a spoke provided at its ends with serew-threads of different pitch engaging in correspondingly - threaded sockets, whereby the rim is tightened by turning the spoke in its sockets, substantially as set forth. 35
13. The rim M, composed of two annular strips of sheet metal bent to the proper form, and having their inner and outer sides overlapping each other, both strips forming a hollow rim having two thicknesses of metal at 40 the central portions of its inner and outer faces, substantially as set forth.
14. The combination, with the rim M, having its face constructed with projecting or raised edges, of a tire, O, constructed with a 45 groove, *o'*, in its outer face, which is closed by forcing the tire into its seat in the face of the rim, substantially as set forth.
15. The combination, with the rim M, of a grooved tire, O, a metallic binder, *p*, arranged in the groove of the tire, and a fastening, *p'*, whereby the tire is forced into its seat in the rim and the groove in its outer face closed, substantially as set forth. 50
